ILLINOIS.

UNCOUPLING DEVICE FOR RAILWAY CARS.

Application filed December 29, 1925. Serial No. 78,196.

This invention relates to uncoupling means for railway cars of that type which are mounted to cooperate with the release pin or key of the usual form of car couplers. 5 The primary object of the invention is to provide a novel form of release elements which are operable from one side of the car, to obviate the necessity of an operative going between the car ends during uncoupling 10 operations, and further, to provide means of this character that may be readily applied to cars now in use and comprising a comparatively simple organization of elements which will be positive in their operation in 15 effecting the function which they are designed to perform.

The invention consists in the construction and arrangement of the several parts which will be more fully hereinafter described and 20 claimed.

In the drawings:

Fig. 1 is an end elevation of a portion of a car and a coupling means diagrammatically represented and showing the improved uncoupling organization applied thereto.

Fig. 2 is a transverse section through a portion of a car end, showing parts of the uncoupling means in full and dotted lines to illustrate the operation thereof.

Fig. 3 is an enlarged top plan view of parts of the improved uncoupling means.

Fig. 4 is a transverse vertical section on the line 4—4, Fig. 3.

Fig. 5 is a view similar to Fig. 4, taken on the same line of section but looking in the opposite direction.

The numeral 5 designates a car of the usual type having an end sill 6 and a coupling head 7 provided with any suitable coupling elements including a pin or key 8.

The improved uncoupling means comprises a keeper and guide secured adjacent one side of the car against the end of the latter and comprising an attaching bracket plate 9 with upper, forwardly projecting jaws 10, which are spaced apart a suitable distance. On the sill adjacent to the coupling head 7 is fixed a base plate 11 of the form shown by Fig. 3, said base plate having a securing eye 12 at one end which is longitudinally straight, and at the opposite end is a second

securing eye 13 which is deflected at an angle in a forward direction. Adjacent to the second or inner eye 13 are upstanding parallel lugs or ears 14 as shown by Figs. 3 and 5, 55 the said lugs or ears 14 extending transversely with relation to the upper part of the plate. At a suitable distance from the lugs or ears 14, longitudinally disposed lugs or ears 15 are formed with and rise from the 60 opposite side portions of the base plate 11 and project upwardly from a web 16, a bifurcation 17 being formed between the lugs or ears 15 as shown by Fig. 4. Between the lugs or ears 14 the rear reduced end 18 of 65 an outwardly projecting arm 19 is pivotally held by a pin 20 extending through the lugs or ears and the said reduced end, so that the said arm 19 will have a free vertical movement. The outer end of the arm 19 is provided with an eye 20^a, to which is attached 70 a link 21 connected to the coupling pin or key 8, as shown by Figs. 1 and 2. Loosely and rotatably mounted between the jaws 10 is an uncoupling rod 22, which is held in 75 connection with the said jaws by a cotter pin 23, the ends of said rod adjacent to the one side of the car being turned down at an angle in the form of a crank handle 24, which is in a position readily accessible to 80 an operative in raising the coupling pin or key 8. The inner extremity of the rod 22 is seated in the bifurcation 17 between the lugs or ears 15 and is held in movable association between said ears by a cotter pin 25, 85 transversely passed through the said ears or lugs. The inner extremity of the rod 22 beyond the inner terminals of the lugs or ears 15 is cranked and forwardly projected as at 26, to provide a raising arm 27, which has a slight upward trend at its terminal 28, 90 as clearly shown by Figs. 1 and 3. The lifting arm 27 continuing from the crank portion 26 at the inner extremity of the rod 22 is located under the arm 19, the latter being normally spaced from the arm 27 to give a certain amount of separation to these parts to compensate for travel of the coupler, and by turning the rod 22 in a proper direction, 95 or by raising the outer crank handle 24, the arm 19 will be elevated when engaged by the arm 27, and through the medium of the link 100

21 attached to the outer end of the said arm 19 the pin or key 8 will be released from the coupling means carried by the coupling head 7 and thus permit uncoupling of the cars.

5 After the lifting arm 27 has performed its work, it drops about one and one-half inches below the arm 19, as clearly shown by Fig. 2, and this position of the said arm 19 together with other features of construction 10 which will now be described allows for uncoupler head travel or removes all tendency to stiffness of the uncoupling features when the cars are traveling and during movement of the coupler head incident to 15 such travel. It will be seen in Fig. 1 that the link 21 which connects the arm 19 to the coupling pin 8 has an eye 21^a at its upper end for loose connection to an eye 20^a at the outer end of the arm 19, and furthermore, at the lower terminal of the link 20 21 is a larger eye 21^b, which connects with the eye at the upper end of the coupling pin 8. The larger eye 21^b and the corresponding larger eye opening permits a loose connection between the lower eye 21^b and the upper end of the coupling pin 8, and the provision of the said larger eye 21^b also causes the lower end of the link 21 to have an offset arrangement relatively to the eye 25 21^a at the upper end of the said link, this offset being due to the enlargement of the eye 21^b. By providing the eyes 21^a and 21^b and the offset due to the enlargement of the lower eye 21^b, there is a freedom of action 30 between the ends of the link 21 and the arm 19 and coupling pin 8, and hence there is no tendency to jam or impose strain on the arm 19 or in any wise exert an upward pull on the coupling pin 8 during travel of 35 the cars and corresponding movement of the coupling head 7. This is a very important feature in the construction and practical operation of the coupling pin lifting means or uncoupling organization. Another feature is that the link 21 is in one 40 piece and therefore cannot kink, foul or drop between the coupler and striking plate, and as a consequence the said link is always in position for instant operation 45 to effectively release the coupling pin 8.

It will be seen that the improved uncoupling means may be readily applied to cars now in use, there being no material modification of structure required, it only being necessary to apply the bracket plate 9 as 50 shown by Fig. 1 and the base plate 11 carrying the lugs or ears 14 and 15, and then associate the rod 22 with the jaws 10 of the bracket plate and the ears 15 rising 55 from the base plate and also secure the said rod in operative relation to the arm 19 by inserting the cotter pin 23 through the jaws 10 and the cotter pin 25 through the ears or lugs 15.

60 65 Structurally, one of the main advantages

of the improved uncoupling means is the base plate 11, which has the ears or lugs 14 and 15 formed integrally therewith, and thereby application and securement of the said base plate with the lugs or ears rising 70 therefrom will at one operation properly position the inner working parts of the improved means. It will also be seen that the uncoupling means is of simple construction and can be economically manufactured and applied.

What is claimed as new is:

1. In an uncoupling means for railway cars of the class specified, the combination with a coupling mechanism including a 80 movable locking device, of a freely movable, forwardly projected arm, a one-piece link connection between the locking device and the projected arm and having eyes at the upper and lower terminals to compensate for vertical and lateral movement of the coupling mechanism during travel, and a rod operable from the side of the car and having a rotatable mounting, the said rod being formed with projecting means under 85 and adapted to engage the projected arm in a plane at right angles to the latter to release the movable locking device from its coupling position, the said means being disengaged from and assuming a position below the rod after it has performed its work.

2. In an uncoupling means for railway cars of the class specified, the combination with coupling mechanism including a movable locking device therefor, of a forwardly projecting lifting arm mounted for movement in a vertical plane, a one-piece link having eyes at the upper and lower extremities thereof respectively engaging the free terminal of the lifting arm and the end 100 of the locking device, the lower eye of the link being larger than the upper eye, and means operable from the side of the car having a projecting portion under and adapted to engage the said lifting arm for 105 releasing the locking device, the said projecting portion automatically becoming disengaged and normally located at a distance from the lifting rod when in normal position.

3. In an uncoupling means for railway cars of the class specified, the combination with a car end and coupling mechanism applied thereto and including a vertically movable locking pin, of means applied to the car end adjacent the coupling mechanism and having bearing devices, an arm having its rear end pivoted between the said bearing devices and projected forwardly, a rod extending inwardly over a portion of the end of the car and having its outer end cranked and located adjacent one side of the car, the said rod being held in the bearing devices and having a cranked portion located under the said arm for 115 120 125 130

engagement with and elevation of the arm, the rod being rotatable in the bearing devices, and a one-piece link having eyes at the upper and lower extremities thereof respectively engaging the outer end of the said arm and the one end of the coupling pin, the lower eye of the link being larger than the upper eye and the link permitting

unrestricted loose movement to compensate for the movement of the coupling mechanism. **10**

In testimony whereof we have hereunto set our hands.

HARRY ACKROYD.
ALFRED W. POWELL.
